Primary Examiner — Kimberly Barnes

(57) **CLAIM**

The ornamental design for a handheld vacuum cleaner, as shown and described.

DESCRIPTION

FIG. 1 is a top, front and right side perspective view of a handheld vacuum cleaner showing my new design;
FIG. 2 is a top, rear and left side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of portion 9 in FIG. 1;
FIG. 10 is an enlarged view of portion 10 in FIG. 1; and,
FIG. 11 is an enlarged view of portion 11 in FIG. 2.
The broken lines in the drawings illustrate portions of the handheld vacuum cleaner that form no part of the claimed design.
